ATTORNEY

UNITED STATES PATENT OFFICE

OTTO M. BRATRUD, OF SEATTLE, WASHINGTON

ADJUSTABLE CUTTING INSTRUMENT

Application filed July 5, 1927. Serial No. 203,556

My invention relates to and has for a purpose the provision of a simple, practical, and durable instrument by which the manual manipulation of a blade in the cutting or scraping of any article is greatly facilitated.

It is also a purpose of my invention to provide a cutting instrument in which the blade is provided with two cutting edges either of which may be presented for use and 10 adjustable to expose more or less of the cutting edge to suit the particular purpose for which it is being used.

I will describe only one form of adjustable cutting instrument embodying my invention, 15 and will then point out the novel features thereof in the claims.

In the accompanying drawing:

Figure 1 is a view showing in side elevation one form of cutting instrument embodying my invention.

Figs. 2 and 3 are views in side elevation, and Fig. 4 a perspective view of the main parts of the instrument shown in Fig. 1 disconnected from each other.

Fig. 5 is a vertical sectional view taken on the line 5—5 of Fig. 1.

Fig. 6 is a view showing the instrument in bottom plan.

Fig. 7 is a detail view of the blade embodied in the instrument.

Fig. 8 is a detail perspective view of the blade holder.

Figs. 9 and 10 are sectional views taken on the lines 9—9 and 10—10, respectively, 35 of Fig. 5.

Referring specifically to the drawings, my invention in its present embodiment comprises a casing including a relatively long tubular section M, and a short section M', the 40 two sections being detachably connected to each other by the provision of a tubular extension 15 on the section M' which is exteriorly threaded for engagement within a threaded portion 16 of the section M, all as clearly 45 illustrated in Fig. 5. The section M' is tubular in part to provide a chamber 18, the remainder of the section being solid with the exception of a slot 17 which communicates with the chamber to receive a blade B carried by a holder H and in such manner that

one end of the blade can project from the free end of the casing section. This end of the section constitutes the working end of the casing and as shown in Figs. 1, 4 and 5 it is tapered in form to facilitate operation 55 of the blade in cutting or scraping.

As shown in Fig. 7 the blade B has oblique end edges which are sharpened to provide cutting edges as indicated at 19 and 19^a, respectively. Between its ends the blade is provided with an opening 20 for receiving a pin 21 on the flat side 22 of a shank 23, the latter constituting part of the holder H. The holder also includes a head 24 on the upper end of the shank 23, and extending upwardly 60 from such head is a sleeve 25 interiorly threaded to receive the threaded portion of a rod 26. The rod is provided with a cap 27 by which the rod can be rotated in one direction or the other to effect a longitudinal 65 adjustment of the holder H as a unit within the casing to vary the projected position of the blade B.

As clearly shown in Fig. 5, the cap 27 is provided with a knurled portion 27^a which is 70 adapted to be gripped in effecting rotation of the head. It is locked against displacement from the casing section M by the provision of an annular groove 28 therein in which is seated an annular bead 29 formed 75 in the casing section by instriking the latter.

With the parts of the instrument assembled as illustrated in Figs. 1 and 5, the head 24 and the sleeve 25 are disposed within the section M, while the shank 23 projects into the 80 chamber 18 to hold the blade B extended into the slot 17. It is important to note that the shank 23 is formed with an oblique shoulder 23^a against which one cutting edge is adapted to bear in order that the blade may be properly positioned to move longitudinally within the slot 17.

By rotating the cap 27 the blade holder H is moved in one direction or the other within the casing thereby effecting longitudinal adjustment of the blade B so that the cutting edge presented to the working end of the casing can be projected any desired distance within the range of adjustment of the holder. It will be understood that movement of the 100

holder H in either direction imparts a corresponding movement to the blade B through the operative connection provided between the two by the pin 21. This operative connection is maintained at all times by virtue of the longitudinal alignment of the flat side 22 of the shank in respect to the slot 17 whereby the blade is at all times engaged by the pin.

10 By forming the blade B with the two cutting edges 19 and 19^a and mounting the blade on the holder H as described, it is possible to reverse the blade on the mounting to present either cutting edge to the working end 15 of the casing so that when one cutting edge becomes dull the other can be employed. It is to be noted that the working end of the casing is likewise formed with an oblique edge so that the supporting surface provided thereby with respect to the blade may be parallel 20 to the cutting edge thereby minimizing the possibility of breaking the blade during use, and particularly when scraping. By reason of the ready detachability of the casing sections from each other, the facility with which the blade B can be reversed or a new blade substituted will be apparent. The casing in practice will be of a diameter slightly exceeding that of a pencil or pen so that it can be 25 carried in the pocket, and to retain the instrument against accidental displacement from the pocket, a conventional clip 30 is secured to the section M.

Although I have herein shown and described only one form of adjustable cutting instrument embodying my invention, it is to be understood that various changes and modifications may be made herein without departing from the spirit of the invention and the 40 spirit and scope of the appended claims.

I claim:

1. A cutting instrument comprising a casing, a holder within the casing, a blade carried by the holder and adapted to project 45 from the casing, a threaded sleeve on the holder, a threaded rod engaging the sleeve, and means rotatable in the casing for actuating the rod to effect an adjustment of the holder through the medium of said sleeve 50 whereby an adjustment of the blade is secured, the holder including a shank having a flat side against which said blade bears, and a pin projecting from the flat side of the shank and engaging the blade for securing 55 the latter to the shank.

2. A cutting instrument comprising a casing, a holder within the casing, a blade carried by the holder and adapted to project 60 from the casing, a threaded sleeve on the holder, a threaded rod engaging the sleeve, and means rotatable in the casing for actuating the rod to effect an adjustment of the holder through the medium of said sleeve 65 whereby an adjustment of the blade is secured, the blade having two cutting edges

and being mounted on the holder to permit reversal thereof so that either cutting edge can be projected from the casing.

3. A cutting instrument comprising a casing, a holder in the casing, a blade carried by the holder and adapted to project from the casing, and means operable from a point exteriorly of the casing for actuating the holder to effect an adjustment of the blade whereby its cutting edge can be projected 70 various distances from the casing, the holder including a shank having a flat side against which said blade bears, and a pin projecting from the flat side of the shank and engaging the blade for detachably securing the latter to the shank, the casing having an opening through which the blade projects, with the walls of the opening operating to definitely 75 guide the blade and maintain it in engagement with the pin.

4. A cutting instrument comprising a casing composed of two sections detachably connected to each other, one of the sections having a tapered end provided with a slot, a blade holder having a head disposed within the other casing section and a shank projecting into the first casing section, said shank being provided with a flat side having a pin, a blade extending into the slot and engaging the flat side of the shank, said blade having 80 its opposite ends sharpened to provide cutting edges and an opening therein for receiving said pin, an interiorly threaded sleeve on the head, an exteriorly threaded rod engaging 85 within the sleeve, a cap on the rod for rotating the latter, and means for rotatably securing the cap within the casing.
